UNITED STATES PATENT OFFICE.

BASIL HEBER TILSTON, OF LATCHFORD WITHOUT, NEAR WARRINGTON, AND THOMAS MELBOURNE, OF WARRINGTON, ENGLAND.

APPARATUS FOR TREATING HIDES AND THE LIKE.

Application filed October 2, 1918. Serial No. 256,561.

To all whom it may concern:

Be it known that we, BASIL HEBER TILSTON and THOMAS MELBOURNE, subjects of the King of Great Britain, residing at 5 Latchford Without, near Warrington, and Stockton Heath, Warrington, both in the county of Lancaster and Kingdom of England, respectively, have invented certain new and useful Improvements in or Relating to 10 the Apparatus for Treating Hides and the like, of which the following is a specification.

This invention has reference to apparatus for treating hides, skins and other goods, 15 of the type wherein the goods are suspended in a pit or vat containing liquor, such liquor being kept constantly agitated not only for the purpose of preventing the essential parts of the liquor settling to the bottom, 20 but also to cause an agitation or movement of the goods to be set up while so suspended in the solution.

Now the present invention is characterized by this, that the liquor is agitated in the 25 pit or vat so as to set up a current between the goods in an upward direction and to exert a pressure between the folds, also to impart to the goods a gentle motion, by means of a stirrer device located under the goods 30 so as to operate in the space between the suspended goods and the bottom of the vat. This upward current is assisted according to 35 the present invention by making the pit or vat with a bottom made concave or in the form of an inverted arch.

We will describe the invention more especially in connection with the unhairing of 40 hides or skins by the action of a liquor containing lime which dissolves the hair sheath so as to enable the hair to be removed when taken out of the lime pit, but it must be understood that the invention is also applicable for bleaching or otherwise treating hides 45 and other goods that are suspended in liquor contained in a pit or vat.

The invention will be understood from the following description reference being had to the accompanying drawings in which:—

Figure 1 is a sectional elevation of the apparatus wherein the blades are suspended from trunnions located near the top of the vat so as to sweep over the concave bottom from end to end of the vat.

Figure 2 is a plan view thereof, one part

of which shows the hides suspended in position and the other part the hides removed,

Figure 3 is a cross sectional view,

Figure 4 is a sectional elevation of the apparatus wherein the blades are mounted on trunnions located near the bottom of the vat so as to rock up and down,

Figure 5 is a plan view thereof, and

Figure 6 is a cross sectional view.

In Figures 1, 2 and 3 the pits are shown arranged in pairs, there being any suitable 65 number of pairs arranged side by side, and the mechanical stirrers of a pair of pits are operated by a single eccentric which is driven by a first motion shaft which passes overhead above a plurality of pairs of pits, 70 there being an eccentric for each two pits.

Referring first to these Figures 1, 2 and 3, 1 indicates a pair of pits or vats which are similar to those in common use in tanneries except that the bottom 2 is made concave 75 like an inverted arch while the sides and ends 3 of the pit are vertical. This concave bottom is important as will hereinafter appear. The liquor in each pit is agitated by mechanically operated stirrers. These stirrers each comprise a pair of swinging arms 4 located at the sides of the pits so as to leave space for a number of hides 5 to be suspended between them, and carrying at 80 the lower ends a paddle or blade 6 and supplementary paddles 7 all of which extend across the width of the pit under the hides 5 and connect the two arms 4 together. The paddle 6 which is so set that its faces are 85 vertical when the arms are hanging vertical are spaced away from the concave bottom about $1\frac{1}{2}$ inches or thereabouts, so that it will sweep over the curved bottom 2 when the arms are rocked, while the supplementary paddles 7 which are located rather further away from the pit bottom, are set in an inclined position like a span roof but spaced apart at their adjacent edges so that they lie one at each side of the plane of the vertical paddle 6. The supplementary paddles 90

are supported by cross pieces 8 bolted to the arms 4. If desired these supplementary blades may be arranged to hit the lower depending edges of the hides as the blades sweep over the curved bottom of the pit.

100 Each pair of swinging arms is provided with trunnions 9 journalled in bearings 10 near the top of the pit and at mid length

thereof also parallel to the axis of the inverted arch 2; the upper ends of the arms extending above the trunnions to a point a short distance below the top of the pit. The stirrers are rocked by means of an oscillating shaft 11 journalled in bearings bolted to the dividing wall of the pits, the said shaft being oscillated by an eccentric 12 and eccentric rod 12* on the first motion shaft 13 and a crank arm 14, cranks 15 on the said oscillating shaft 11 being coupled by connecting rods 16 to the upper ends of the arms 4, so that a pair of stirrers are operated by a single eccentric, and with equal energy in each direction. At opposite ends of each pit near the top that is parallel to the axis on which the stirrers rock, suspender rails 17 are fixed, to which rails are secured a plurality of pins or hooks 18. The hides or skins to be treated are first straightened out and folded along the back from the head to the tail and suspended on ropes or slings 19 which are connected at the opposite ends to the hooks or pins on the suspender rails so as to take up a position with the belly downwards, and at right angles to the axis 9 upon which the paddles rock, so that the circulation of the liquor set up by the stirrers shall be longitudinal of and between the hides. The trunnions project from one side only of the swinging arms so that a clear space is left between the arms for the hides or skins to be suspended, and the connecting rods being at the sides of the pit do not obstruct the hides in any way.

The pits 1 are filled in the usual manner with water, and the requisite quantity of lime is put in unslaked, or the lime may be previously prepared in a lime hole and then deposited in the pit 1, all stones being first removed. The hides 5 are then placed in a suspended position in the pit so as to be at right angles to the axis on which the paddles swing, the eccentric 12 is put into gear, the rocking of the paddles commences, and the heavier matter in the liquor which gravitates towards the lowest part of the concave bottom 2 is dispersed by the action of the stirrers impinging against it and forcing it outwards towards the ends 3 of the pits, and from thence back again so that a thorough agitation is set up, and the liquor becomes uniformly and heavily charged with the lime. The vertically set blades 6 ensure a circulation of the liquor longitudinally of and between the hides 5 alternately in opposite directions while the oblique blades 7 force the heavier matter in the liquor towards the surface. The current set up also causes a rise and fall of the liquor at each stroke and exerts a pressure inside the folds of and between the hides 5 in addition to the longitudinal movement, which gives a gentle but most

useful motion to the hides themselves. The constant agitation of the liquor tends to create a uniform strength of liquor throughout the entire pits, and ensures the penetration of the liquor to all portions of the hair and pelt so that hair sheath is dissolved in much less time than under the usual methods, and the hides are plumped quicker. When the process has been completed, the hides are taken out of the pits, and drained, or they can be drained by opening the plug hole 21 which communicates with a drain pipe or trunk 22 by which the liquor in the pits can be discharged. The hides when taken out of the pits have the hair removed by an unhairing knife or unhairing machine. The ground level is indicated at 20. Instead of the cords or slings 19, beams or battens might be used over which the folded hides are laid. The impinging of the oblique blades against the hides, as the blades sweep over the curved bottom of the pit, is also responsible for a gentle motion being given to the hides themselves.

Referring now to Figures 4, 5 and 6, 1 as before is the pit or vat having a concave bottom 2 like an inverted arch, and 24 are paddles or blades provided with trunnions 25 journalled in bearings 26 at the centre of the concave bottom and in proximity thereto, so that they will rock up and down, the axis of these trunnions 25 being by preference at right angles to the axis of the inverted arch 2. These blades have a number of apertures 27 in them each controlled by one way valves 28, these valves being preferably flap valves arranged in rows, the valves in each alternate row opening and shutting upon one hinged side 29 and the valves in the intermediate rows opening and shutting upon the opposite hinged side. The blades 24 are rocked up and down on their trunnions 25 by an eccentric 30 and eccentric rod 31 on the first motion shaft 32, the eccentric rod being coupled to one of the blades, so that when the hides 5 are placed in the vat and the vat filled with liquor, the valves in the blades at opposite sides of the trunnions will open and close alternately, those at one side opening when their blade descends so as to allow the liquor to pass through them, and closing when the blade rises so as to lift the liquor and cause an upward current thereof, and the same action is caused by the other blade. This upward current is assisted by the inverted arched bottom 2. Thus the rocking of a blade downwards, causes the valves to open upwards and allows the liquor and lime to pass through, while the valves in the other blade are closed and disperse the lime upwards between the hides towards the surface. Moreover the hinging of the valves 28 to open and shut on opposite hinged sides 29 produces a number of cross

currents in the liquor and provides an even distribution of the liquor over the hides suspended in the vat. Consequently the liquor becomes uniformly and heavily charged with the lime and a thorough circulation of the liquor is ensured, together with a rise and fall of the liquor at each stroke. The trunnion bearings 26 are shown embedded in the concave bottom 2 of the ¹⁰ vat.

The two apparatus described above are also applicable for bleaching or otherwise treating hides, cotton fabrics and other goods that are suspended in liquor within ¹⁵ a pit or vat as will be obvious without further description.

One great advantage resulting from the use of this invention, is the expediting of the process of dissolving the hair sheath to ²⁰ enable the hair to be removed, this being a very important consideration, because the shorter the time the hides remain in the liquor, the less will be the amount of hide substance which is dissolved by the chemical combinations that take place in the pit, and consequently a larger return of leather is obtained. A further advantage is that the lime is so thoroughly and uniformly distributed throughout the liquor, that a loosening of the hair and a softening of the ²⁵ epidermis is obtained by the use of a smaller quantity of lime than hitherto.

The usual method of treating hides hitherto used prior to this invention necessitates ³⁰ the handling of hides 5 or 6 times, while the present invention enables the tanner to prepare his hides for unhairing without any labour whatever after they are placed in the pit.

We declare that what we claim is:— ⁴⁰

1. An apparatus for treating hides and the like, comprising in combination, a vat for liquor having a concave bottom, means to suspend the hides thereon in spaced relation, and an agitator having a substantially vertically disposed blade and a blade inclined to the horizontal, means for sweeping said blades in alternate reverse directions across the bottom of the vat so as to cause the vertical blade to force a circulation of liquor longitudinally of and between said hides alternately in opposite directions and to force the heavier particles in said liquor upward toward the surface of said liquor. ⁵⁰

2. In an apparatus for treating hides or other goods in which the goods are held suspended in a pit or vat, a stirrer device therefor comprising arms mounted for swinging movement in said vat, a paddle carried by said arms, said paddle including faces arranged to be in substantially vertical planes when said swinging arms are perpendicular, supplementary paddles carried by said arms and set in an inclined position ⁶⁰ like a span roof, but spaced apart at their adjacent edges so as to lie above and one at each side of the plane of the vertical paddle. ⁶⁵

In witness whereof we have hereunto ⁷⁰ signed our names this 23rd day of August, 1918, in the presence of two subscribing witnesses.
